UNITED STATES PATENT OFFICE.

FRANK E. KRESS, OF DENVER, COLORADO.

BRUSH-MAKING MACHINE.

1,141,398.

Specification of Letters Patent.

Patented June 1, 1915.

Application filed August 12, 1913. Serial No. 784,417.

To all whom it may concern:

Be it known that I, FRANK E. KRESS, a citizen of the United States of America, residing at the city and county of Denver and 5 State of Colorado, have invented a new and useful Brush-Making Machine, of which the following is a specification.

My invention relates to improvements in brush making machines for automatically 10 filling the backs of brushes with bristles; and the objects of my invention are: First, to provide a machine that will automatically fill one complete row of bristles, hair or any other suitable material used for 15 brushes, into metal, composition, or wooden brush backs. Second, to provide a machine for automatically filling twelve bundles of bristles, hair or any other suitable material used for brushes, at one revolution of the 20 machine, also wiring the twelve bundles complete. Third, to provide a machine for separating the required amount of bristles, hair or any other suitable material used for brushes, for making twelve full separate 25 bundles, these being then gripped by the gripper and carried to the proper position by the gripper holder and inserter guide, the twelve bundles to be then inserted by the twelve inserters or the gang inserter. I 30 attain these objects by the mechanism illustrated in the accompanying drawings, in which:

Figure 1, is a front elevation of the improved machine for automatically filling the 35 backs of brushes with bristles. Fig. 2, is a side elevation of the same. Fig. 3, is a vertical longitudinal section through the forward portion of the machine, showing the bundle carrier in position over the brush back. Fig. 4, is a longitudinal section 40 through the machine, showing the bundle carrier swung to a vertical position, and the gripping device in position for receiving the bunches of bristles from the hopper. Fig. 5, 45 is a rear elevation partly in section of the cross-head which supports the needles and needle guiding sleeves. Fig. 6, is a side elevation of the same, partly in section. Fig. 7, is a vertical sectional view of the same 50 showing the parts constituting the cross-head at the limit of their downward positions. Fig. 8, is a horizontal section through the cross-head showing the manner of securing the needles therein. Fig. 9, is a 55 horizontal sectional view through the aux-

iliary or sleeve supporting cross-head, showing the manner of securing the needle guiding sleeves. Fig. 10, is a fragmental horizontal sectional view through a portion of one side of the machine, showing the comb, 60 the gripping device, and the means for locking the movable member of the gripping device. Fig. 11, is a front elevation of the shuttle guide and shuttle, showing the bundler which is hinged in a recess in said shuttle. Fig. 12, is a vertical sectional view 65 through the shuttle guide, the shuttle, and the bundler. Fig. 13, is a fragmental horizontal sectional view through a portion of the shuttle guide, shuttle and bundler, showing 70 the spring for returning the said bundler to its normal position. Fig. 14, is a plan view of a portion of the oscillating plate which carries the needle guide and bundle gripping device. Fig. 15, is a front 75 elevation of the stationary member of the gripping device. Fig. 16, is a front elevation of the slidable member of the gripping device. Fig. 17, is a vertical section through the parts shown in Figs. 15 and 16 when 80 they are assembled. Fig. 18, is a side elevation of the locking plate which secures the slidable member of the locking device in its locked position. Fig. 19, is a plan view 85 of the anvil portion of the machine, showing the movable arm which carries the brush back supporting die and the wire feeding and cutting device. Fig. 20, is a longitudinal vertical sectional view—full size—of the inner end of the swinging arm, showing the 90 die carried thereby, the brush back upon said die, and the means for removing the bristles with the brush back. Fig. 21, is a horizontal sectional view of the wire feeding plunger. Fig. 22, is a vertical longitudinal 95 sectional view of the wire feeding and cutting mechanism. Fig. 23, is a transverse section of a portion of the machine on the line 23—23 of Fig. 4. Fig. 24, is a front view of a portion of the guide plate showing 100 the needle guides, some of which are broken away for clearer illustration. Fig. 25, is a side view of a portion of a modified form of needle sleeve plate and modified form of needle projecting therefrom. Fig. 105 26, is a horizontal sectional view thereof on the line 26—26 of Fig. 25.

Similar letters of reference refer to similar parts throughout the several views.

Referring to the drawings, the numeral 1 110

designates a base-plate which is provided with apertured bolt or lag-screw receiving lugs 2, by which it may be secured to a suitable foundation block or to a substantial 5 bench. Upon this base-plate I mount a pair of standards 3 and 3^A, which extend vertically up from the base-plate, and may be cast integral with the base-plate or may be detachably secured to it. I preferably 10 detachably secure them to the base-plate by bolts 4. These standards are positioned a few inches apart, and they are each provided on their front end portion with a slideway 5. These slideways comprise vertically arranged finished step portions 6, which are formed on the front edges of introverted lug portions 7, which are formed on the front end of the standards. A gib 8 is removably secured to the front of each 15 standard by cap screws 9, which together with the finished step portion in the lugs forms a square shaped guide slot in each lug. In these slide-ways I reciprocably mount a cross-head 10. This cross-head 20 comprises a substantially square shaped casting provided with enlarged vertical side edges, which are finished to slide reciprocably in the guideways of each standard. This cross-head is provided with a central 25 lug 11 at its upper end, which is divided by a slot 12 into ears 13, through which a pivotal pin 14 extends. One end of a connecting rod 15 fits in the slot 12 between the two ears, and is secured to them by the pin 30 14, which extends through them. The opposite end of this connecting rod is pivotally connected to a double sided crank-arm 16, by a pivotal bolt 17, which extends through the crank arm and the end of the 35 connecting rod. The two crank arms that form this double crank arm are secured to the adjacent ends of two shaft sections, which are journaled in alinement with each other, and when connected together through the 40 medium of the double crank-arms by the bolt 17, form one shaft. Consequently hereinafter this double arm crank-shaft and the two shaft sections will be referred to as 45 crank shaft 18. This crank shaft 18 is journaled in bearings 20 and 21, that are formed in the top ends of the standards 3 and 3^A. These bearings are provided with removable 50 cap portions, which permit the crank shaft to be lifted out of the bearings when necessary.

A cam 22 is mounted on the crank shaft on the inside of the standard 3, and between its bearing 20 and the crank-arm 16, which engages a roller 23, that is housed in one end 55 of a rock-arm 24, which is pivotally secured intermediate of its ends by a bolt 25, to the inside of the standard. The opposite end of this rock-arm is pivotally connected to one end of a lever 26, the opposite end of 60 which is pivotally connected to one end of

a projecting lug 27, that is cast on a hub 28, which is provided at each end with a stub-shaft 29 which extends through bearings 30 formed on the standards below the cross-head guideways 5. A cam 31 is also mounted on and is secured to the crank-shaft 18, on the inside of the standard 3^A, and between it and the crank arm. This cam 31 engages a roller 32, that is rotatably mounted in one end of a lever 33, which is mounted in a slideway block 34, which is bolted on the inside of the said standard. The opposite end of this lever is pivotally secured to a projecting lug 38, that is formed on the hub 28. This hub 28 is provided with a projecting plate portion 39, which is arranged and adapted to be moved reciprocably from a vertical position to a horizontal position, and upon the outer edge of this plate portion 39, a gripping and holding mechanism 40 is secured, which is arranged to receive the bundles of bristles from a bristle separating shuttle, and a bundling comb, which are arranged to separate the bristles from the hopper, as will be explained more fully herein-after.

On the crank shaft outside of the bearing of the standard 3^A, a disk 40 is mounted and secured, in which a laterally moving spring controlled pawl 41 is mounted, and engages the ends of two arms 42 and 43, the function of which will be explained more fully hereinafter. The pawl 41 however acts to automatically couple the crank shaft to a suitable registering coupling disk or device, which may be driven by an electric or any other suitable motor. I do not illustrate the power driven part of the coupling or the motor, as they do not comprise any part of my present invention.

The crank shaft 18 extends beyond the journal box 20 and a cam 42^J is mounted on and is secured to it. This cam comprises a hub of metal having a spiral groove 42^K, formed in its peripheral surface, along the 110 larger portion of its length, which is arranged to give a horizontal traveling movement to a pin 43^B, that fits loosely in it and that is secured in one end of a rock arm 44, which is pivotally secured by a pin or bolt 45, to a bracket 46, that is secured to the side of the standard. The opposite end of this rock-arm is bifurcated to form a slot 48 which fits loosely over a headed-pin 49, that is secured to the rear end of a 115 separator bar 50, which is slidably mounted in a laterally extending arm 51, in which a slideway 52 is formed, that is adapted to receive the shuttle-bar, which is arranged to reciprocate in it. The inner end of the 120 bar 51 has a rearwardly extending portion 51^A, at right angles to the body of the arm, and is secured to one side of a hopper supporting frame 53, that is adjustably secured by screws 54, to stepped bearing strips 55, 130

that are formed on rearwardly extending bracket portions 56, that are preferably cast integral with the standards. The slot in the arm 51, in which the shuttle bar reciprocates, is preferably a T-shaped slot; and the shuttle bar is a thin strip of metal that fits loosely and slidably in it, and the pin to which the bifurcated end of the rock arm 44 is secured, is attached to the rear end of the shuttle. The front end of the shuttle is provided with a pointed terminal end which I term the bristle separating point, and which is adapted to move across the discharge end of a hopper 57, which rests in the supporting frame 53, and separate from the hopper a thin layer of the bristles at each forward movement imparted to it by the spiral grooved cam and the rock arm. The shuttle bar is provided with an elongated rectangular slot, which is located close to its shuttle end, and in this slot I pivotally mount a bristle bundling plate 58, which I term the "bundler," and which comprises a strip of metal of the length of the brushes to be made, which is provided along its lower edge with wedge-shaped pointed teeth 59. This bundler receives the bristles from a comb 60, and this comb and bundler in the machine herein illustrated, would be the length of the brush to be made, and as the length of the brush would be the length of the brush back to which the bristles or hair is secured, this bundler is made to receive the bristles from the comb, and is arranged and adapted to separate them into the number of bundles of bristles or hair required for the length of the brush back. This bundler normally stands in a vertical position, and is arranged to be swung up into a horizontal position at the end of each forward stroke of the separating shuttle, by means of a spring controlled rock-arm and lever mechanism, which consists of a flat strip 61, which I term a push finger, and is provided with a slot 62, and is secured slidably to the under side of the hopper supporting frame 53 by headed screws 63, which extend through the slot in the strip and screw into the bottom of the hopper supporting frame. A depending pin 64 is secured to this push strip and is loosely connected to the end of an L-shaped rock-arm strip of metal 65, which is pivotally secured to the adjacent side of the hopper supporting frame, by a screw 66, and its end that is connected to the pin 64 is provided with a bent end that is provided with a hole, through which the pin 64 projects, so that when this push strip is moved reciprocably it moves the end of the rock-arm strip that is connected to it by the pin 64. The upper end of its rock arm is provided with a slot 66^A, and a rod 67 is secured at one end to this lever by a headed pin 68, which is secured to the end of the rod 67, and projects

through the slot 66^A. The pin 68 also projects far enough beyond the end of the rock arm to receive one end of a coiled contraction spring 69, the opposite end of which is connected to a screw 70, which is secured to the side of the hopper supporting frame. The rod 67 extends through a slot 67^A formed in the inside surface of the right angled end portion 51^A of the shuttle supporting arm, and its free end rests close enough to the lower edge of the bundler to engage and swing the bundler up into a horizontal position on its pivotal trunnions. The rod 67 is moved to do this in the following manner: When the plate 39 of the hub 28 is moved from a horizontal position to a vertical position by the engagement of the cam 31 with the lever 33, an adjustable abutment screw 71 carried by said plate, engages the end of the push rod 61, which is positioned in its path and slides it rearwardly on its pin 63 a short distance, and as it moves back it carries with it the lower end of the rock-arm 65, which is connected to it and moves its top end to push the rod 67 against the bundler 58 and raise and hold it in a horizontal position; the object of this is to allow the bundler to divide with its pointed wedge shaped teeth, the thin layer of hair or bristles that the shuttle separates from the hopper, into small bundles or bunches as the points of its teeth when they move up through the bristles divide them and separate the bristles between the points of each pair of adjacent teeth from those between the other points of the teeth, and these independent bunches or bundles of bristles are still held by their upper ends by the comb 60, and at their lower ends by a foot plate 72, that extends across the end of the hopper supporting frame and projects a short distance above its floor. Consequently the bundler divides the bristles into bundles and holds them momentarily in that position until they are seized by a gripping device, which is secured to the edge of the inserter guide or plate 39 of the pivotal hub 28, which device grips them and moves them over the brush back. The mechanism for gripping the bundles of bristles in the teeth of the bundler will be described hereinafter. As soon as the bundles have been gripped, the inserter guide 39 moves with the gripping mechanism away from the bundler and the push finger, the spring 69 draws the rod 67 away from engagement with the bundler and moves the rock-arm and push strip forward to their normal position ready to be acted on again by the plate 39 at its next upward movement to the bundler. The bundle is drawn instantly down into its vertical position by a coiled spring 75, which is mounted on a pivoted pin 76, one end of the pin being secured to the shuttle bar, and one end of the spring resting upon the

shuttle bar, while the other end of the spring is connected to a pin 77, carried by the adjacent end of the bundler.

The hair or bristles holding hopper of my improved brush making machine consists of three parts, namely the hopper supporting frame 53, which comprises a rectangular open top trough-shaped casting, that is secured to the bracket extensions of the standards, and extends rearwardly from them, an open top open ended hopper member 57, that fits loosely within the supporting frame and in which the bristles are placed, and that is preferably made of sheet metal such as sheet brass, and which is filled with hair or bristles that are stacked on end and which have previously been cut to the desired length, and a pressure feeding device 78, which I term a pressure feeder, that fits slidably within the hopper proper, and that is arranged to exert a constant pushing feeding pressure against the bristles in the hopper. I preferably carry out this feature in the following manner: The pressure feeder 78 comprises a long casting member which fits slidably in the hopper 57, and is provided with an end wall 79, that is of the same height as the hopper and faces the bristles in the hopper, and at the outer end of this pressure feeder I secure to it a bar 80, that extends a short equal distance beyond each side, and to each of its end portions I secure the end of a wire rope 81, which extends to and over a pulley 82, that is pivotally mounted on a pin 83, that is secured to the inside of the brackets of the standards, and to the end of each rope I secure a weight 84 that is heavy enough to exert a constant pressure of sufficient force to keep the wall end of the pressure feeder forcing the bristles through the hopper as fast as the shuttle and bundler and the gripper takes them from it.

The comb 60 is provided with end strips 85, which are secured to the front end of the hopper supporting frame by any suitable means, preferably by being welded thereto. This comb 60 comprises a bar portion that extends across the end of the hopper, and this bar is provided with a row of wedge-shaped or saw teeth 87, that are formed along its inner edge, and that are arranged to face toward the interior of the hopper, and this comb is provided with the same number of teeth as the bundler is, and from the pointed end of each tooth a small round pointed prong of wire 88 projects for a short distance, the teeth and pointed prongs being arranged to project substantially in a horizontal plane and parallel with the bottom of the hopper, and they act to separate the bristles in the hopper, as the said bristles are moved by the pressure feeder between the said prongs and into the spaces between the saw teeth, where they are crowded into

a narrowing wedge-shaped space, which bunches the top end portions of the bristles in bundles, and to that extent assists the bundler, at each forward movement or stroke of the shuttle.

Above the comb an adjustable plate 89, which I term a feed plate, is mounted on screws 90, which are threaded loosely into small hubs 92, which are formed on the supporting strips 85 of the comb. The screws 90 are provided with large head portions, in each of which a circumferential groove 91 is formed, dividing the head into two collar portions and leaving a small neck portion 94^A between the collars. The feed plate is a thin strip of metal, which extends above the teeth of the comb and close to them, and its opposite ends are provided with slots 95^A which are arranged to fit over the necks 94^A of the screws, thus supporting the ends of the plate between the collar portions of the heads of the screws. This feed plate is adjusted to allow bunches of even size to work into the teeth of the comb, by moving it slightly along the teeth of the comb by turning the screws 90, which should be adjusted to keep the bunches of bristles collecting between the teeth of the comb, as even in size as possible. This is accomplished by turning first one screw and then the other, until the desired adjustment is made. To the feed plate 89 is secured a rearwardly extending horizontal plate 93, the rear edge of which is slightly upturned. As the bristles pass under this plate, they are thereby pressed down, so that their ends are all on the same horizontal plane.

The bundle gripping mechanism comprises the oscillating hub 28 and its plate 39, the lever 26, and the levers 24 and 33, which are operated by the cams 22 and 31 as above described. The plate 39 is provided at its free end with a bundle gripping and carrying device, and also with a bundle folding and receiving and a needle receiving guide plate. Inasmuch, however, as the bundle gripping and carrying mechanism operates in each cycle of the machine's movement before the needle guide is brought into use, I will describe it first, and it consists of the following instrumentalities, and operates in the following manner. This gripping device is positioned on the extreme outer edge of the plate 39, and comprises a bar 94, which I term the fixed grip bar, which is provided with a central longitudinal slot, so that the bar is U-shaped in cross section, as shown in Fig. 17. Upon its upper closed or solid edge portion, a plurality of teeth 95 are formed, each of which has a hook shaped terminal end projecting slightly toward the right hand side of the machine. The teeth and their hooks are all made of the same size and shape and the hooks all project in the same direction. The slot in

the grip bar extends throughout its length from its under side, and extends up through the hooked teeth to close to their top edges. This fixed grip bar is secured rigidly to the 5 end of the plate by screws 96, which extend through its opposite ends, and are threaded into threaded apertures formed in the ends of the plate to receive them. A plate 97, which I term the reciprocating grip plate, 10 is slidably mounted in the slot of the grip bar, and its upper edge is provided with hooked teeth, and this plate is arranged in the bar with its teeth fitting up into the teeth of the bar and facing them. The ends 15 of this grip plate extend beyond the ends of the bar 94, and are provided with oblong slots 99, that extend through it, and they are arranged to fit loosely over the screws 96. This reciprocating grip plate is arranged so that its hooked teeth are intermittently moved from behind the teeth of bar 94 into the spaces between them, and up to the 20 ends of the teeth of the said bar 94, and surrounds and grips between them the bundles of bristles and hair separated from the 25 hopper by the shuttle and the bundler, and carries them to a position directly over the brush back 98 ready to be pushed down into the bristles or hair receiving pan. This 30 fixed grip bar 94, and the plate 97, within it, constitute what I call the bristles or hair gripping mechanism. The intermittent reciprocating movement of the plate 97 is imparted to it to move it toward and to the 35 fixed teeth of the bar 93, to cause it to grip the bundles of bristles or hair in the bundler, by means of a vertical slide bar 101, and a rock arm 102, which is actuated in one direction of its rocking movement by a cam- 40 lug 103, that projects from the side of the cam 31, and in the other direction by a spring 103^A, which is secured at one end to it and at its other end to the inside of the standards, and which is arranged to return 45 the rock arm to its normal position as soon as the cam 103 has left it.

As the cam 31 is rotated by the revolutions of the crank shaft, the cam lug 103 thereon engages a roller 104, that is mounted 50 at the end of the rock arm 102, which is pivotally mounted on a screw or headed pin 105, which is threadedly secured to the side of the standard 3^A, and tilts the roller end of this rock-arm down, and raises its opposite 55 end, which is pivotally connected by a headed pin 106 to the upper end of the slide bar 101. This slide bar 101 is slidably confined in a guideway slot 107, that is formed in a block 108, that is pivotally secured to 60 the side of the standard by a screw 109. A guide strap 111 is also secured to the upper end of the block by the screw 109, which strap extends over the adjacent side of the slide bar and holds it loosely in the guide 65 slot against accidental displacement from

the guide slot in the block 108. This arrangement of guides for the slide bar 101 causes its lower end to move up and down in a vertical path, and at its end it is provided with a laterally projecting cam surface 113, which as the slide bar is raised by the cam lug 103 of the cam 31 of the crank shaft engages a projecting knob 114, that is formed on the adjacent end of the grip plate 97, which is arranged to be engaged by the 70 cam when it is moved back so that it is at the end of its backward or open stroke movement, and its teeth are behind the teeth and are consequently covered by the teeth 95 of the grip bar 94 of the bundle gripping 80 device. Then when the cam 113 engages the projecting knob 114, it moves the reciprocating grip plate inwardly a short distance, and moves its teeth out from under the teeth into the clear space between them and up to 85 and against the ends of the hooked teeth of the fixed grip bar, closing them around the bundles and locking or gripping them between the fixed and movable hooked teeth. The fixed grip teeth of the bar 94 are arranged to register exactly with and to pass under and a trifle beyond the teeth of the bundler, when the bundle gripping device is swung up to meet the bundler and shuttle. Consequently the fixed gripping teeth of the 90 bundle gripping device straddle the bundles held in the teeth of the bundler device, and when the gripping device has reached the end of its bundler engaging movement, its reciprocating grip plate is moved inwardly 100 by the cam 113, and surrounds the grips and holds the bundles between its teeth and the teeth of the fixed grip bar. Then as the crank shaft continues to rotate, this gripping plate is swung downward into its horizontal position over the bristle or hair receiving pan ready for the next operative movement of the machine, which is to release the bundles from the bundle gripping and carrying mechanism and deliver them free 105 to the needle guide 115, and the plunger-needles, which operation is as follows: When the gripping mechanism moves down close to the bristles receiving pan, it strikes a spring plate 116, which normally rests just 110 above the pan, and is engaged by the under side of a lug portion 117 of the plate 39 that is formed into what I term a needle and bundle guide, and is pressed down against the pan, as will be fully described hereinafter. 115 This needle and bundle guide 115 comprises the lug portion 117, that is formed on the end of the plate 39, and projects above and below the plate far enough to form a guide for the needles 119, which are positioned directly above it. This needle and bundle guide comprises a plurality of pointed wedge-shaped teeth arranged in a straight row, there being preferably eleven pointed 120 and two half teeth, one at each opposite end 125

130

portion of the plate, making twelve teeth spaces, between the eleven whole and two half teeth of the needle and bundle guide, and between each two teeth a guide aperture 120 is formed, which extends vertically down through the lug and forms guide apertures for the needles 115, which move reciprocally in them with a close but slideable fit. There are consequently 12 apertures in the twelve teeth spaces of the needle and bundle guide, and there are also twelve teeth spaces and eleven pointed teeth in the bundle gripping device and shuttle, and there are the same number of teeth and spaces in the bundle forming device, and also the same number of teeth and spaces in the comb at the end of the hopper, and there are twelve wire shaped teeth projecting from the points of the wedge-shaped teeth of the comb into the hopper in my present machine, and they make brushes having twelve bundles in a row. The bundle gripping device is secured to the outside surface of this needle and bundle guide portion of the hub 28 and plate 39 by the screws 96, which guide portion is machined to receive it, and it is arranged in such relation to the needle and bundle guide portion that they stand parallel to each other, and with the teeth of the gripping device in alinement with the teeth of the needle guide so that the bundles of bristles in the spaces between the teeth of the gripping device lie naturally in the spaces between the teeth of the needle and bundle guide. Consequently when the hub 28 is turned by the crank shaft and its connecting levers to cause its plate portion 39 to swing up from its flat horizontal position over the brush pan holder to its vertical position, the teeth and spaces between them of the bundle gripping device and the needle and bundle guide register with the teeth and spaces of the bundler device, which in turn registers with the teeth and spaces between the teeth of the comb, when the shuttle is at the forward end of its stroke, and the bundles at the time they are embraced and locked to the gripping device lodge naturally in the spaces between the teeth of the needle and bundle guide, as these teeth come up and register in alinement with the teeth of the bundler, but they pass under them far enough to allow the teeth of the guide to partially surround the bundles in the bundler, while the gripping device is surrounding and locking to them. Then when the needle and bundle guide is moved back down again to its horizontal position over the pan holder, the bundles are held in the gripping device about half way of their lengths, and they lie in the spaces between the teeth of the needle and bundle guide with the center of the lengths of the bristles at the center of the width of the teeth and of the diameter of the needle guide apertures in the spaces be-

tween the teeth, ready to be first released from the gripping device, and second to be doubled up into a U-shape and pushed down through the needle guide apertures into the apertures in the pan.

The needle mechanism for loading the bundles of bristles into the brush backs comprises a vertical row of sleeves 121, which are reciprocably carried in the cross-head 10 in a cross bar 122, that through the first and greater part of the downward movement of the crosshead is locked to it and travels downward with it, and through the remaining portion of the cross head's downward movement remains stationary, and the cross-head moves down against it. These sleeves extend into apertures that are drilled entirely through the bar, and the sleeves are hollow throughout their whole length and are secured in the apertures in the bar by pins 124, which are arranged to extend into apertures drilled centrally between each alternate pair of sleeves and through the opposing sides of said sleeves, so that when the pins are driven into the aperture they fit into the recesses in the sleeves and thus key them to the cross-bar. These sleeves act as guides for a row of needles 119 that are secured in apertures in a plate 126 by set-screws 127. The plate is removably secured to the cross head by screws 128. There are twelve of these needles and consequently twelve of these sleeves.

The sleeve supporting cross-bar is reciprocably mounted in the cross-head of the standards, and is locked to travel with it in the following manner: This cross-bar is supported by two pins 130, which are threaded one at each end into the ends of the cross-bar. These pins extend loosely up into apertures 131 and 132, drilled vertically through the cross-head. The larger hole 131 is drilled down from the top of the cross-head to near the bottom of the cross-head, where it stops, and the aperture 132 is continued down through the cross-head. The pins are provided with slotted heads 133, that fit loosely and slideably in the holes 131, and the body of the pins fits slideably in the holes 132, and they are turned by a suitable screw driver, which is inserted in the aperture, and they are screwed into the ends of the cross-bar. The pins with their heads extend only part way through the holes in the cross-head, and above the pins a coiled expansive spring 134 is placed in each aperture, and rests on the head of each pin. The upper entrance ends of the apertures 131 are threaded and a nut 135, which is provided with a screw slot, is threaded therein, and arranged to be adjustably turned down into these apertures to adjust the tension of the springs against the heads of the pins. Consequently a constant downward pressure is exerted upon the heads of the pins 130,

by the spring 134, whereby the cross bar 122, with the sleeves 121, is returned to its normal position, at the end of each bristle-inserting operation, as will be hereinafter fully explained, and the downward movement of this cross-bar is defined by the heads 133 of the pins 130 striking against the shoulder 139 formed at the bottom of the aperture 131. The sleeve supporting bar 10 is positioned a short space below the lower edge of the cross-head, but the sleeve supporting bar is slidably mounted so that, as the cross-head descends, this cross-bar is stopped by engagement with an auxiliary cross-head, to be presently described, and which has been moved to rest upon the needle guide, as shown by Fig. 3, and the cross-head moves down on the pins until the lower edge of the needle plate engages the top edge of the sleeve supporting bar, at which point it remains stationary, and the cross-head continues to move down on its pins 130, until it rests on top of the cross-bar 122, as shown by Fig. 7. In order that the sleeve supporting cross-bar may be moved by the cross-head until it engages the said auxiliary cross-head, I provide a spring controlled pawl device, which is carried by the cross-head and which engages the cross-bar and locks it against upward movement, and prevents it from standing still when the cross-head is moving down on its downward stroke, but forces it to be moved down with the cross-head until it reaches the auxiliary cross-head 140, which it engages, and when these parts are bearing on each other and the needle and sleeve guide plate is resting on the brush back die block, these pawls are automatically released, and then the cross-head continues to move down on its pins 130, until it engages the cross-bar 122, when the downward movement of the cross-head terminates. This spring controlled pawl device for locking the sleeve supporting cross bar to the cross-head, comprises a bar 141, which I term a pawl-bar, and which extends parallel with the needle supporting plate 126, and beneath the same, and at each of its opposite ends it is provided with a depending block portion 142, the inner edges of which are provided with the projecting pawl lugs 143, which are made to normally extend over and engage the top surface of the cross-bar 122. This pawl-bar is supported in its normal cross-bar engaging position by two ribbon springs 144, each of which is secured at one end to the needle supporting plate by a screw 145, and the opposite ends of these springs are secured to the pawl bar by screws 146, and these springs are arranged to hold the blocks of this bar against the adjacent side of and its pawl portions extending over and bearing onto the top adjacent edge of the cross-bar, 60 and when the cross-bar moves down with the cross-head, the inside edge of each of the end blocks 142, which are provided with a beveled edge 147, engages oppositely arranged beveled edges formed on the ends of two flat plates 148, which are arranged in the path of the blocks and are secured by a screw 149, to the auxiliary cross-head and sleeve guide 140, and the blocks and pawls of the pawl-bar are forced outwardly far enough to cause its pawls to move back entirely free of the sleeve supporting cross-bar, which allows the pawl blocks to move down along the outside edge of the cross-bar as the cross-head of the standards continues its downward movement after the cross-bar 70 has come to rest on top of the auxiliary cross-head 140. This auxiliary cross-head comprises a cross-beam 150, which extends across the cross-head below it, and at it ends is secured to the lower ends of two vertical square rods 151, which are slidably seated in guideway recesses 152, that are formed in the edges of the cross-head 10, that are slidably mounted in the guideway grooves of the standards. The lower edge of this auxiliary cross-head is provided with a central longitudinal groove, which forms thereon parallel strips 153, each of which is provided with eleven full pointed wedge-shaped teeth and two half teeth, and consequently with twelve intervening spaces between these teeth the same as the comb 60, the bundler, the bundle gripping device, and the needle and bundle guide plate, and this auxiliary cross-beam is provided with a vertical row of apertures that extend down through it and end between these teeth in the spaces between them. This row of apertures is made to receive slidably the lower ends of the needle guide sleeves, as this cross-beam normally stands at a sufficient space below the sleeve supporting cross-bar to support the lower ends of the sleeves, and is reciprocably mounted on them. This auxiliary cross-head beam is held at the limit of the downward stroke of its reciprocable movement in the cross-head of the standards, by an expansive coiled spring 157, which is loosely mounted on a vertically disposed rod 158, that is secured at its lower end to the outer extremity of a bracket 159, against which the lower end of the rod abuts. This bracket 159 is secured to the back of the cross-beam 140 by the screws 149. The upper end of this rod 158 extends loosely through an aperture formed in a lug portion of a truss-plate 162, which extends across the rear edges of the standards, and is rigidly secured to them and acts as a truss to support the upper portions of the standards together. 80

The upper end of the spring 157 bears against the under side of the lug portion of the truss-plate, and this spring is arranged to exert a constant downward force on the 90

100

105

130

cross-beam sufficient to hold it at the end of its downward movement in the cross-head of the standards, so that it will always act as a firm supporting guide for the lower ends of the guide sleeves of the needles.

5 The side bars 151 of the auxiliary cross-head, are provided at their upper ends with laterally projecting pins A¹, which are engaged by shoulders A², on the sides of the cross-head 10, near the upper end thereof, as the cross-head moves upward, thereby lifting the auxiliary cross-head simultaneously with the said cross-head 10. When the cross-head 10 moves down, the auxiliary cross-head 140 moves with it until the teeth of the cross-beam strikes the teeth of the gripping device, when the cross-beam stops and the cross-head 10 continues on its downward stroke sliding on the square rods of the cross-beam 150 until the sleeve supporting cross-bar rests on the cross-beam, and the needle supporting plate rests on the sleeve supporting cross-bar. Consequently at the end of the downward stroke of the cross-head of the standards, the needles and their sleeves and the cross-beam are resting against each other in the order of their vertical arrangement, and the cross-beam is resting on top of the needle and bundle 20 guide plate. The instant the supplemental cross-head engages the guide plate, the bundles are released from the gripping device automatically.

35 The releasing of the bundles from the gripping device is effected as follows: The plate 39 that supports the gripping device is provided with an aperture 154 which enters its end edge, and a pin 155 is slidably mounted in this aperture. A coiled spring 40 156 is placed in the bottom of this aperture behind this pin, and is arranged to bear with an expansive pressure against the end of the pin. The opposite end of this pin extends outside of the aperture, and the end of the plate, and a post portion 163 is formed, which extends across its end at right angles to the pin 155, and which preferably forms an integral part of it. This post portion is positioned between the reciprocating plate 97 45 and the adjacent edge of the plate 39, and is provided with a short projecting pin 164 that is positioned on the post to either bear against the adjacent side of the reciprocating plate 97 of the bundle gripping device 50 or to fit loosely in an aperture 165 formed in this plate to receive it, in which case the adjacent side of the post bears against the side of the reciprocating plate, the post being held under resilient expansive tension 55 against this reciprocating plate by the spring 156. This spring controlled post and pin member I call a locking-bolt, and it acts to lock the reciprocating plate of the gripping device in its bundle gripping relation to the stationary teeth of the bundle 60 65

gripping device, and consequently in its closed position. This reciprocating plate of the gripping device is locked in its closed position at each cycle movement of the machine the instant the bundle gripping teeth 70 close around the bundles at the bundle forming device, and remains locked until the needles are ready to push the bundles down through the apertures of the needle guide plate into apertures 166, of the brush back 75 98, when this plate is released by the withdrawal of the locking pin from the apertures of the plate, which is accomplished automatically by the downward movement of the sleeve supporting cross-bar, the end of 80 one of the strips 153 of which engages an upwardly projecting spur 167, that is formed on top of the post 163 of the locking bolt. This spur 167 of the locking bolt is provided with a beveled edge, which is 85 beveled to slope backward from the front of the machine while the terminal end of the engaging strip 153 of the sleeve supporting cross-bar is provided with a beveled edge 90 that slopes in the same plane upwardly, and is arranged to engage the sloping surface of the spur 167 in such a manner as to move it backward, and consequently the locking bolt against its spring, far enough to move the pin 155 out of the locking aperture of the 95 plate, by the time the cross-bar has moved down against the cross-beam 150 below it. The instant the plate is released from the pin 155 of the locking bolt, this plate springs outwardly to the right under the 100 tension of a spring 168, which is preferably a wire spring that is secured at one end to the opposite corner of the plate 39 of the hub 28, from the locking bolt, and is arranged to throw the hooked tooth plate 105 back in the stationary plate of the gripping device in which it is reciprocably mounted. When this plate 97 has moved back and released the bundles from the hooked teeth of the gripping bar, the guide plate with 110 the gripping device is resting against the brush back 98, which is on the die 169 of the anvil block 170, and the cross beam is resting on the guide plate and the sleeve supporting cross-bar is resting on the cross-beam of the auxiliary cross-head, and these parts have all stopped but the cross-head of the standard continues to move down and the needles, as they emerge from the lower ends of the sleeves, straddle the bundles at 115 120 about the center of their length, and push them down into and through the guide apertures 120 of the guide plate and into and through the apertures of the brush back, where a wire 171 is run through the brush pan and through the loops of the bristles, while the needles are held in the brush back for a second or two, as the cross-head reaches the limit of its downward stroke, and the crank shaft passes its lower centers. 125 130

In Figs. 25 and 26, is illustrated a slight modification in the form of the needle and guide sleeve. In this modification, a sleeve 5^a is employed, which has a concaved, beveled face 5^b, on opposite sides of its lower end and in the extremities of these faces are formed substantially V-shaped recesses 5^c, which terminate in semi-circular crotches. The needle 5^d has similar concaved beveled 5 sides 5^e, and in the lower end thereof is formed a substantially V-shaped recess 5^f, which is wider at its open end than the recesses in the end of the sleeve, and terminates in a semi-circular crotch, which is also 15 of slightly greater diameter than those in the said sleeve recesses. By this means, the bundles of bristles engaged by the sleeves are forced into their crotches, and as the needles descend, their V-shaped recesses being 20 wider than those in the sleeves, will insure their surrounding and engaging all of the bristles carried by the sleeves, and delivering them to the pan without loss of any of the bristles.

25 The brush back illustrated is in the form of a shallow pan and is provided with three rows of bristles or hair receiving apertures 166 for the reception of bristles, and each row holds twelve bundles. The back is also 30 provided with three apertures 172, through its right hand end. These end apertures are positioned each in alinement with one of the rows through the top of the back. The end apertures are arranged and adapted to 35 receive the end of a wire 171 that is inserted through these holes and extends through the loops formed in the bundles by doubling or folding them up when the needles engage them at the centers of the lengths of the 40 bundles, and force them down through the guides 120. The needles on the downward stroke of the cross-head of the standards pass entirely through and beyond the ends of the sleeves into and through the row of 45 apertures of the cap that is directly below them, and they carry the bundles down through the apertures into the cup portion of the back. At this point, the wire is inserted in the aperture 172 that is in alinement 50 with the row of apertures of the top of the cap that the needles are in, and is passed between the end of the needles and the loop end of the bundles.

55 The instant the needles have pushed the bundles down into the apertures of the back at the end of their downward stroke, they start upward and at the instant the needles have moved upward about an eighth of an inch, the machine is automatically stopped by the engagement of the projecting portion of the pawl 41, with the inner face of the arm 42, which releases the said pawl from the clutch on the driving shaft, and bring the machine to a stop, until the attendant can insert a wire in the back through the

loops of the bundles, the slight raising of the needles above the bend in the bundles leaving an aperture in them through which a wire can be easily and quickly inserted.

A coil of wire is supported adjacent to 70 the machine, and its end is gripped and inserted into the aperture in the end of the back that is in alinement with the row of apertures of the pan the needle and bundles are in, and the wire is pushed through the 75 loop of each bundle and to the opposite end of the back. The wire is then cut close to its outside entrance end, leaving the wire in the back in the loops of the bundles, and it firmly secures them against being drawn out 80 of the apertures of the back when the needles move upward out of the back. I preferably employ a manually operated device for manipulating the wire, which is arranged as follows: The back and its die-block 85 are supported on an arm 170 which is pivotally secured at one end to the anvil block 173, by a bolt 174. The die block 169 that the back sets on, is formed on or is secured to this arm. This arm is arranged to 90 be turned on the anvil to occupy three different positions, in order to bring each of the three rows of holes 166, in the back 98, in alinement with the needle guide. To accomplish this, the outer end of the arm is 95 provided with an elongated hole 175, through which the bolt 174 passes, and a spring 176 is secured to the under side of the adjacent end of the anvil, its outer end terminating in a semi-circular portion, which 100 bears against the adjacent end of the arm 170, and normally presses its opposite end against the end of a block 177, which is secured to the anvil. When the forward row of holes 166 is to be filled, the arm 170 is 105 swung toward the rear until it engages an angle plate 178, which is secured to the rear edge of the anvil, and which supports the plate 116, which will be later referred to. When the arm is turned to stand parallel 110 with the anvil, the central row of holes 166 are in alinement with the needle guide, and in this position a catch 179 on the end of the arm is sprung into a recess 180, in the adjacent end of the block 177, by the pressure of the spring 176, whereby the arm is 115 prevented from lateral movement. To bring the remaining row of holes in alinement with the needle guide, the arm 170 is swung outward until it engages the face of a latch 120 181, which is pivoted at one end to the outer face of the anvil, its opposite end being provided with a slot 182 through which passes a screw 183, which enters the face of the anvil, and which limits the swinging movement of the latch.

The latch is normally held at the limit of its upward movement, by a spring 184, which is secured to the under side of the anvil, and in this position, a portion of the latch ex- 130

tends above the horizontal face of the anvil, and forms a stop for the arm 170, as clearly shown by Fig. 1. As above mentioned, a piece of wire is passed through the looped ends of each row of bristles before the next row is inserted. In order to remove the back 98, with the three rows of bristles, from the die block 169, the latch 181 is pressed down and the arm is then swung out to the position shown in Fig. 19. In order that the looped ends of the bristles may not catch in the holes 169 in the die block when the back is removed, I provide means for pushing the bundles from the die block, simultaneously with the removal of the back, as follows: In the arm 170 beneath the die block, I form a recess 185 of equal width with the said block, and in this recess is placed a plate 186, which has a vertical sliding movement on screws 187, which pass loosely through holes in its opposite ends and are screwed into the said arm. The plate 186 is provided with rows of vertically disposed pins 188, which extend into the holes in the die block and partially through them. This plate is normally flush with the bottom of the arm 170, and to remove the bristles with the back the plate is pushed upward in its recess, and its pins 188 engage the looped ends of the bristles and eject them from the said block, as will be fully understood by reference to Fig. 20.

When the first row of bristles has been inserted in the back, the said row will of course stand in a vertical position, and in this position the row would be in the path of the guide plate, as it swings down with the next row of bristles, and would therefore be pressed down and crumpled by the said guide plate. In order to obviate this, I employ the pusher 116, previously mentioned, which comprises a plate having guide slots 189, through which screws 190 pass, and enter the angle-plate 178, upon which the pusher is supported. A U-shaped spring 191 is fastened at one end with the angle plate to the anvil, and the other end of this spring terminates in a reduced portion which extends through a slot 192, in the angle plate, and also through a hole in the rear portion of the pusher. This spring exerts pressure in a forward direction on the pusher, which normally causes it to stand in the position shown in Fig. 4, and assuming that the central row of bristles have been inserted in the pan, the pusher is moved to this position by the spring 191, and bends the row forward so that it will be out of the path of the descending guide plate, and the ends of the bristles will be engaged and deflected by an inclined plate 193, on the outer face of the needle guide on said guide plate. But before the guide plate with the next row of bristles, reaches the limit of its downward movement and rests on the back, the

pusher must be moved back from over the row of holes to be filled, and this is accomplished by a pair of pins 194 which project from the hub 28 of the guide plate, and engage the outwardly turned ends of a U-shaped strip of metal 195, which is secured to the pusher, and as the guide plate completes its downward movement, the pusher reaches the position shown in Fig. 3, and is held in this position until the guide plate is swung up again, moving the pins 194 out of engagement with the ends of the strip 195, and thus permitting the pusher to resume its normal position.

The wire feeding and cutting mechanism is arranged as follows: Secured upon the anvil, so that one of its ends abuts against the block 177, is a plate 196, the opposite end of which extends slightly beyond the adjacent end of the anvil. This plate is provided with a longitudinal dove-tailed groove 197, which extends throughout its length. A block 198 extends a short distance into the outer portion of this groove, and is secured therein by a set screw 199, which extends through the bottom of the plate and engages said block. This block has an offset portion 200, which abuts against the end of the plate, and upon which are mounted three grooved wire-guiding rollers. Two of these rollers 201, are in line with each other and separated by an intervening space, and the third roller 202 is of slightly greater diameter than the other two, and is mounted above and between them, to an adjustable plate 203, which is attached to the offset portion 200 of the block. The grooves of these rollers are in line, and the larger roller extends slightly in between the other two rollers so as to exert a tension on the wire and straighten the same as it is fed forward. Within the groove 197, is slidably mounted a block 204, to which is attached an operating handle 205, having a slight pivotal movement thereon. The block 204 has a groove 206 in its upper face in line with the grooves in the wire guiding rollers, and at the inner end of this block and intersecting the groove 206, is a screw 207, having a long head, which is slotted from the top down to a point on a level with the bottom of the said groove 206. In this slotted screw is pivotally mounted an L-shaped arm 208, the vertical member of which has a tooth on its lower end which is adapted to engage the wire which lies beneath it in the slot of the screw. The horizontal portion of the arm 208 lies over and engages a finger 209 on the operating handle, which causes its tooth portion to be slightly embedded in the wire, so that when the plate 204 is moved forward in the groove 197 by the operating handle, the wire is carried with it.

The block 204 is provided with parallel longitudinal holes 210, in which are placed

- coiled springs 211, against which bear the rear ends of rods 212, the forward ends of which are secured in a cross-head 213, that is also slidable in the dove-tail groove 197.
- 5 This cross-head has a tubular wire guide 214, through which the wire passes to a guide 215, in the form of a screw having a hole through its head through which the wire passes. This latter guide is carried by 10 the block 177. On opposite sides of the guide 215, are pivotally mounted blades 216 and 217 respectively, which are provided with wire cutting edges at their ends adjoining the end of the arm 170. The blade 15 216 runs parallel with the anvil, and the blade 217 stands at right angles thereto, and when the handle is pushed forward, the blade 216 is engaged and rocked on its pivot by an inclined face on the end of the finger 20 209, while the blade 217 is engaged by the end of a projecting member 218, on the handle 205. By this means, the cutting edges of the cutter blades 216 and 217 are caused to sever the wire flush with the end 25 of the bristle holding back, the severing of the wire occurring when the handle reaches the limit of its inward movement, when it is rocked slightly on its pivot as the end of the projection 218 passes over the 30 inner end of the plate 196, which causes a quick snapping action of the cutters. The cross-head 213 supports the wire between the wire gripping dog 208 and the guide 215, and as the block 204 is moved forward, 35 the cross-head engages the block 177 and is stopped, and the block continues, until it engages the rear edge of the cross-head, when the wire-severing operation occurs. Thus the whole distance traveled by the 40 block 204 corresponds to the length of wire which is inserted in the back between the looped ends of the bristles. The cross-head rods 212 are provided with heads which engage shoulders in the holes in the block 45 204, and the rear ends of these holes are closed by screws as shown. Backward movement of the wire is prevented, by a toothed dog 219, which is pivotally mounted between ears 220 on the block 198. This dog 50 is held in contact with the wire by a U-shaped spring 221, the ends of which are coiled around the pivot of the dog, while the connecting member thereof rests upon the top of the dog, as shown.
- 55 The machine is automatically stopped by the trip arm 43, as before described, in order that the gripping operation may be inspected; and again by the trip arm 42, to give the attendant time to insert and cut 60 the wire. These trip arms are rocked on a common pivot bolt 42^A, to release the pawl 41, by wires 42^B and 42^C respectively, which extend from the arms and are secured to a lever 42^D, which is pivoted at one end to a 65 stud 42^E, which is screwed to an arm 42^F, which extends from the inner edge of the anvil. The wires pass through a guide tube 42^G, which is screwed into the said arm 42^F, and the downward movement of the lever 42^D is limited by a headed screw 42^H, which 70 passes through a hole in the handle portion of the lever and is screwed into the anvil for a portion of its length. The trip arms are returned to their normal positions by a coiled spring 43^A, which connects the two 75 arms, as shown in Fig. 2. Sagging of the feed follower 78 of the bristle hopper, is prevented by an arm 78^A, which is secured to the under side of the hopper support, and carries a roller 78^B at its free end, which 80 bears against the bottom of the said follower.
- The operation of the improved brush filling machine is as follows: The hopper is filled with bristles of the required length, 85 and which stand in a vertical position in the hopper, and the feed follower 78 automatically presses the said bristles forward against the ledge 72 at the end of the hopper, and also against the plate 89, the comb 60 90 serving to split the bristles near the feed end of the hopper in separate bunches or groups. Assuming that the rocking plate 39 is in a horizontal position, the cam 31 engages the upper end of the arm or lever 95 33, which is attached to the crank arm 38 of the rocking plate, and as the said lever is pushed down by the cam, the plate 39 is moved up to a vertical position. At the same time, the cam 42^J rocks the arm 44 100 by which the separator bar 50 is moved across the face of the hopper, and a layer of bristles, which were previously separated into groups or bunches, is separated from those in the hopper. 105
- The cam groove 42^K has a straight portion 2^A, which serves to hold the separator bar stationary, at this point, for a short period, and as the plate 39 assumes a vertical position, the bundler 58 is swung out by 110 the rod 67, in the manner above described, carrying with it the bundles of bristles which are thereby pushed in between the teeth 95 of the stationary member 94 of the gripper. At this point, the knob 103 on the cam 31 engages the roller end of the rock arm 102, by which the lever 101 is raised, and its cam face 113 engages the projection 114 on the end of the sliding member 97 of 115 the gripper, and slides the same forward so that its teeth, coöperating with those of the fixed member 94 of the gripper, engage the bundles of bristles, and when the said sliding member reaches the limit of its movement, the hole 165 in its outer end registers with the pin 164, on the member 163, which is thrown out by the action of the spring 156, thereby projecting the pin 164 through the hole 165, and locking the plate 97 against the action of its spring 168. 120 125 130

The cam 22 then moves into engagement with the rock arm 24, which draws on the lever 26, and rocks the plate 39 to a horizontal position, in which position it rests on the 5 brush back 98, and the guide holes 120 in the plate register with one of the rows of holes in said back. Meantime, the cross-head 10 is descending, with the supplemental head 140, which is forced down simultaneously with the cross-head 10, by the spring 157. The supplemental cross-head engages the end of the plate 39, before the cross-head 10 reaches the limit of its downward movement, and as its parallel toothed members 153 straddle the end of the lug portion 117 of said plate through which pass the holes 120, the corner 28 of the outside toothed member 153 engages the inclined face of the projection 167, on the spring-20 pressed member 163, forcing the said member rearward, so that its pin 164 is disengaged from the hole 165 in the slideable gripper plate 97, and the said plate is thrown to release the bundles of bristles, by the 25 spring 168. The cross-head 10 continues its downward movement, and the recessed ends of the needle-sleeves 121 straddle the bundles of bristles, which lie across the holes 120 of the plate 39, and double or fold them 30 centrally, and force them down through the said holes 120 until their folded or looped ends stand slightly above the holes in the back, at which point the sleeve-carrying bar 122, is stopped by engagement with the 35 member 150 of the supplemental cross-head, and the beveled ends of the trip plates 148 engage the beveled portion 147 of the blocks 142, at the ends of the bar 141; and the dogs or catches 143, which are carried by said 40 blocks, and which engage the upper edge of the bar 122, are thereby released from said bar, permitting the cross-head 10 to continue and complete its downward movement. This further movement of the cross-head 45 pushes the needles 119 out through the ends of the sleeves, and the looped bundles are thereby pressed down through the holes 166 in the back 98, thus completing one bristle receiving and inserting operation. At this 50 juncture the machine is automatically stopped in the manner before described, and the handle 205 attached to the wire feeding mechanism is manually moved to insert the wire in one of the holes 172 in the end of 55 the pan, and along through the looped portions of the bundles of bristles until its end contacts with the opposite end of the back, when the wire is severed in the manner before described. The arm 170 is then moved 60 to bring the next row of holes in the back in line with the needles, and the lever 42^D is pressed and the pawl 41 thereby disengaged from the arm 42, and the above operation is repeated, the pins 194 on the hub 28 of the plate 39 releasing the pusher plate 116, 65 which is then moved forward by its spring 191 to engage and press the row of bristles forward so as to be out of the path of the outer end of the plate 39, on its downward movement. The operation is continued until 70 all the rows of holes in the back have been filled, after which the back, with the bristles, is removed from the die block 169 by the plate 186, and its pins 188, in the manner previously set forth. 75

Having described my invention, what I claim as new and desire to secure by Letters Patent, is:

1. In a brush making machine, the combination with a support for a brush back, 80 provided with a plurality of bristles receiving apertures, of a supporting frame, a hopper supported by said frame, provided with a weight controlled force feed plate, said hopper being arranged to receive bristles 85 stacked on end and arranged vertically, a comb device at the discharge end of said hopper provided with pin teeth arranged to extend into the bristles and divide them into independent groups at the discharge end of 90 said hopper, a reciprocating separator arranged to separate said groups of bristles from said comb and hopper, a toothed bundler bar on said separator arranged to swing up from said separator and engage 95 said separated groups of bristles and separate them from the grouping comb of the hopper into bundles, a bundle gripping device and carrier arranged to grip the bundles when in the bundler and to convey them 100 in operative relation to a brush back on said apertured support, said gripper comprising means including a fixed hooked bar and a reciprocating hooked tooth bar arranged to surround and grip to said bundles, and 105 means including reciprocating needles and guide sleeves for inserting said bundles in the bristles receiving apertures of said brush back. 110

2. In a brush making machine, the combination with a supporting frame, an apertured-block on said frame adapted to support a correspondingly apertured brush back in position to receive the brush making bristles or hair, of a pressure feed hopper 115 connected to said frame, means including a comb device for dividing the bristles at the discharge end of said hopper into individual groups, means including a shuttle device for separating said groups of bristles from said hopper and for assembling them into bundles, means including an oscillating bundle gripping device for gripping said bundles 120 at the shuttle and conveying them in inserting relation to said brush back, guide sleeves on said oscillating gripping device arranged in alinement with the bristles receiving apertures of said brush back, and reciprocating 125

plunger needles arranged to push said bundles through said guide sleeves into the apertures in said brush back.

3. In a brush making machine, the combination with a supporting frame, a crank-shaft mounted on said frame, a power driven clutch arranged to rotate said crank shaft, means including spring controlled pawls for automatically throwing said clutch out of engagement with said crank shaft at two predetermined points in its rotative movement, a die block on said frame adapted to receive a brush back, provided with rows of bristles receiving apertures and also with wire receiving apertures in one end, a reciprocable wire gripping device arranged to insert a wire in the apertures in said back, a bristles holding and feeding hopper on said frame, means including a graduating feed plate at the discharge end of said hopper, means including a reciprocating shuttle device and an oscillating separator and bundler attached to said shuttle for grouping said bristles into bundles, means including an oscillating plate, a fixed hooked tooth bar on said plate and a reciprocating hooked tooth plate arranged to coöperate with the fixed bar to surround and grip the bundles and convey them in operative relation to said bristle receiving back, and means including guide sleeves adapted to receive said bundles and reciprocating needles arranged to push said bundles down through said sleeves into the bristles receiving apertures of said back, and means connected with said wire inserting device for inserting a piece of wire in said back in engagement with said bundles whereby they are secured in the apertures of said back against accidental displacement.
4. In a brush making machine, the combination of a base plate, a pair of standards mounted on said base plate, a crank shaft journaled in the upper end of said standards, a cam mounted on and secured to said crank shaft, a crank arm pivotally secured to the adjacent standard and provided with a roller at one end which is in engagement with said cam, a lever pivotally connected at one end to the opposite end of said crank arm, a hub provided with trunnion shaft portions journaled in said standards below said crank shaft, a lug projecting from said hub, said lug being pivotally connected at its outer end to the opposite end of said lever, a plate portion projecting from the opposite side of said hub from said lug, said hub and plate having an oscillating reciprocating movement about a quarter of a circle, said cam and rock arm and lever being arranged to swing said plate from a vertical position down to a horizontal position on the downward stroke of its swinging movement, a bristles holding and feeding hopper sup-

ported by said frame having its feed end 65 adjacent to the vertical position of said plate, means including a reciprocable device for separating and bundling the bristles in operative quantities from said hopper, means including a cam mounted on said crank 70 shaft and a lever pivotally connected to a lug portion of said hub and provided with a roller at its opposite end for raising intermittently said plate on the upward swinging stroke of its oscillating reciprocating 75 movement, a bundle gripping device on the outer end of the plate of said hub, means including a cam lug and lever mechanism for locking said gripping device when in operative relation to said bundler, and bundle receiving guides on said plate at the side of said gripping device, and arranged to receive bundles of bristles from it, and means for rotating said crank shaft.

5. In a brush making machine, the combination with a support adapted to receive a brush back, of a supporting bed plate, standards secured to said bed plate, a vertically reciprocating cross-head slidably mounted in said standards, a connecting rod pivotally 90 connected at one end to said cross-head and pivotally connected to the crank portion of said crank shaft at its opposite end, a set of bundle engaging and inserting needles mounted in said cross-head, each of said 95 needles being removably secured to said cross-head and provided with flattened chisel ends containing a tapering recess extending transversely across the flat edge of each needle, a bristles receiving hopper mounted on said frame, means including a comb and a separator for adjustably feeding bristles from said hopper, and for grouping them into bundles, a bundle gripping device arranged to grip the bundles adjacent to said separator, and carry them in operative inserting relation to said brush back guide apertures for said needles, and means for imparting a reciprocating movement to said cross-head and operative movement to its coöperative mechanism.

6. In a brush making machine, the combination of a supporting base plate, an anvil block on said base plate, a pivotally swinging arm on said anvil block, a block on said 115 anvil's swinging arm adapted to receive a brush back having bristle receiving apertures and wire receiving apertures, standards on said base block, a cross-head reciprocally mounted in said standards, a row of 120 bristles inserting needles in said cross-head, means to secure said arm in positions on said anvil to lock said brush back in positions that will bring each of its bristle receiving rows of apertures one at a time in 125 alinement with the row of needles of said cross-head, said die-block being also provided with rows of apertures registering

- with the apertures in said brush back and adapted to form clearance spaces for said needles, and means including a hopper and a comb and a separator, a bundle gripping, 5 carrying and releasing and a needle guiding mechanism arranged and adapted to convey bundles of bristles from said hopper in operative engaging relation to said needles and in inserting relation to the 10 bristles receiving apertures of said brush back, said needles being arranged to fold said bristles and form a loop at their inserting ends and to push said folded looped end into and through the apertures of said brush 15 back into its interior, and means for inserting a wire in the wire receiving apertures of said pan through said brush back and the loops of said bundles, whereby said bundles are secured to said brush back by said wire.
- 20 7. In a brush-making machine, the combination of the supporting base plate and frame, of the anvil, the pivotal swinging arm on said anvil, and the die block on said swinging arm, adapted to receive a brush 25 back provided with a plurality of bristles receiving apertures, a cross-head slidably mounted in said frame, means including a crank shaft for reciprocating said cross-head, a row of needles removably secured to 30 said cross-head, each of which is arranged to force bundles of bristles into the apertures of said back, a row of sleeves on said cross-head in and through which said needles reciprocate into and through the 35 apertures of said back, said sleeves having a sliding movement up onto said needles, slideways in the edges of said cross-head, and an auxiliary cross-head slidably mounted in the slideways of said cross-head, said 40 auxiliary cross-head and said needle guiding sleeves having each a reciprocating movement in said cross-head, they being arranged to engage the bundle gripping mechanism of said machine on the downward 45 stroke of said cross-head or to stop in successive order while the cross-head moves down against them, and to be held until the cross-head on its upward stroke has risen above them until they occupy their normal 50 positions, when they are carried upward on the further upward stroke of said cross-head, said auxiliary cross-head being provided with a row of apertures arranged to receive and act as guides for the lower ends 55 of the needle guide sleeves of said cross-heads, and means including springs for returning said guide sleeve's supporting bar and said auxiliary cross-head to their normal positions below said cross-head.
- 60 8. In a machine as specified, the combination with a bristle-receiving hopper, a follower for pushing bristles toward the discharge end of said hopper, means for separating the bristles into independent 65 bundles, and means for separating the bundles of bristles from those in the hopper, of an adjustable support, and a back on said support having rows of bristle-receiving apertures, a swinging member having bristle receiving apertures, means secured to the 70 swinging member for gripping the bundles and conveying them to a position above said back, a cross-head, means for reciprocating the same, a guide mounted in said cross-head having apertures corresponding to those in the swinging member, and adapted to rest on the swinging member with their apertures registering; sleeves carried by said cross-head and extending through said guide, and adapted to bend the bundles of 75 bristles and insert them in the apertures of the swinging plate, and needles in said sleeve for pressing the folded ends of the bundles into the apertures in the back.
9. In a machine as specified, the combination with an adjustable brush back support and a brush back thereon having rows of apertures, an oscillable plate having a row of apertures adapted to register with one of the rows of apertures in said brush back, when 80 in one position, and a gripping device carried by said plate, for receiving bristles in independent bundles which lie across the apertures in said plate, of means for bending and pushing said bundles through the apertures in said plate and into said brush back, comprising a reciprocating main cross-head, a bar resiliently supported by said cross-head below the lower end of the same, having a row of downwardly extending sleeves 85 90 95 100 with beveled lower ends having V-shaped recesses, means for locking said bar to travel with said cross-head, needles carried by said cross-head which extend into said sleeves but not beyond their lower ends, a supplemental cross-head slidably mounted in the main cross-head having guide apertures for said sleeves, resilient means for causing the supplemental cross-head to descend with the main cross-head, and pins carried by the 105 supplemental cross-head which are engaged by the main cross-head thereby to raise the said supplemental cross-head, said supplemental cross-head first engaging said oscillable plate, the main cross-head continuing 110 its downward movement until the sleeve carrying bar rests upon the supplemental cross-head, and tripping means for disengaging the locking means as said bar engages the supplemental cross-head, whereby 115 the main cross-head continues its downward movement until it engages said bar, when the needles are projected through and beyond the sleeves.
10. In a machine as specified, the combination with a support having rows of apertures therein, and a brush back thereon correspondingly apertured, a bristle receiving hopper, means for separating portions from the bristles, means for separating said por- 120 125 130

- tions into bundles, a plate having gripping mechanism for receiving said bundles and apertures corresponding to the bundles, and means for swinging said plate away from said hopper and against said brush back with their apertures registering, of a reciprocable cross-head mounted in said frame in line with said brush back, a frame resiliently and slidably connected to said cross-head and below the same, having sleeves, needles carried by said cross-head and extending partially through the sleeves, a supplemental cross-head slidably mounted in the first cross-head, having guides through which the sleeves extend, a spring for moving the supplemental cross-head down simultaneously with the first cross-head until it engages the apertured end of the swinging plate, means for locking the sleeve holding bar to the first cross-head, means for releasing the said bar as it contacts with the supplemental cross-head whereby the continued movement of the first cross-head carries the ends of the needles beyond the ends of the sleeves, and pins carried by the supplemental cross-head which are engaged by the main cross-head as it moves upward, thereby lifting the said supplemental cross-head.
11. In a machine as specified, the combination with a support having rows of apertures and adapted to receive a similarly apertured brush back, a swinging plate having apertures corresponding with those in the brush back and provided with a gripping mechanism for receiving bundles of bristles so as to lie across said apertures, of means for pushing said bundles of bristles through said apertures and into the apertures of the brush back, comprising a reciprocable cross-head, a supplemental cross-head carried by the first cross-head and extending below the same, a bar intermediate of the first cross-head and the supplemental cross-head, having rods which extend into openings in the first cross-head, springs in said openings which exert a downward pressure on said rods, and spring dogs for locking said bar to said first cross-head, sleeves projecting from said bar through the supplemental cross-head, having beveled lower ends, with V-shaped recesses therein, needles in said first cross-head which extend partially through said sleeves, a spring for moving said supplemental cross-head downward simultaneously with the first cross-head until it engages the swinging plate, means for disengaging the said dogs as the cross-head descends, and the sleeve bar engages the supplemental cross-head, whereby further movement of the first cross-head causes the needles to project beyond the sleeves, and means for raising the supplemental cross-head simultaneously with the main cross-head.
12. In a machine as specified, the combination with a support and a brush back thereon, said support and brush back having registering rows of bristle receiving apertures, a hopper, a hinged plate having a gripping mechanism for conveying bristles from said hopper to said brush back, and means for inserting said bristles in said brush back, of means for holding one row of bristles out of the path of the descending plate carrying another row of bristles, comprising a support, a plate slidably mounted on said support, the forward end of which is adapted to engage a row of bristles, a spring for normally pressing the plate forward, and means carried by the hinged plate for moving the sliding plate rearward, as the hinged plate reaches the limit of its downward movement.
13. In a machine as specified, the combination with a hinged plate having a bristle gripping mechanism and bristle receiving holes, an adjustable support having rows of apertures, and adapted to receive a similarly apertured brush back, and means for inserting the bristles carried by said gripping device into said brush back, of means for pressing a row of inserted bristles out of the path of the descending hinged plate, comprising a support, a push plate mounted on the support, having parallel slots and screws passing through said slots into the support, a spring for normally pressing the push plate forward, lateral projections on said push plate, and pins carried by said hinged plate which engage said lateral projections and move the push plate rearward as the hinged plate reaches the limit of its downward movement.
14. In a machine as specified, the combination with a frame, a bristle holding hopper in said frame, a pressure follower therein, means for separating layers of bristles from those carried by the hopper, means for separating the layers into separate bundles, a hinged plate having bristle-receiving apertures, and a gripping mechanism for receiving the said bundles, of means for rocking said plate, comprising crank arms at opposite ends of its hinged end, and levers pivoted to said crank arms, one of which has a roller at its upper end; a shaft mounted in said frame having a crank portion, cams on said shaft on opposite sides of said crank, one of said cams being adapted to engage the said roller in one of the levers to cause the hinged plate to move from a horizontal to a vertical position; a rock arm, one end of which is pivoted to the upper end of the other lever, its opposite end carrying a roller which is engaged by the other cam, whereby the hinged plate is moved from a vertical to a horizontal position, an adjustable support having rows of apertures adapted to register successively with the apertures in 180

the hinged plate when the same is in a horizontal position, said support being adapted to receive a similarly apertured brush back, a cross-head mounted in the frame above and in line with the brush back, means carried by the cross-head for folding and for inserting the bristles carried by said gripping means, through the apertures in said hinged arm and into said brush back, and an arm connecting the cross-head and the crank portion of the said shaft.

15. In a machine as specified, the combination with a suitable frame, a bristle-receiving hopper mounted therein, an automatically operating pressure feed follower in said hopper, a guide secured to one side of said hopper and flush with its discharge end, a power-driven shaft on said frame, a cylindrical head on one end of said shaft having a cam groove therein, a bracket on the frame, a rock arm pivoted intermediately of its length to said bracket, one end of which is slotted, a reciprocable separator in said guide having a pin engaged by the 20 slotted end of said arm, the opposite end thereof having a pin which enters the said cam groove, whereby the separator is given a reciprocating movement thereby to separate layers of bristles from those in the hopper, a comb over the discharge end of the hopper for dividing said bristles into bundles, an adjustable plate for defining the thickness of said layers, means for preventing irregularities in the horizontal plane of the 25 bristles as they pass to the comb, and a toothed bundler hinged within a recess in said separator, for withdrawing the said bundles from the hopper, in combination with a support adapted to receive a bristle receiving brush back having rows of apertures, means for conveying the bundles from the said bundler to a position over the brush back, and means for inserting the bristles in the aperture in said brush back.

30 16. In a machine as specified, the combination with a suitable frame, a bristle receiving hopper mounted therein, and a pressure feed follower in said hopper, of a reciprocable shutter for separating layers of bristles from those in the hopper, means for dividing said layers of bristles into bundles, a toothed bundler pivotally mounted in an opening in said shuttle, for withdrawing said bundles from the hopper, a hinged plate 35 having a gripping device for receiving the bundles, means for rocking the same from a vertical to a horizontal position, a support and a brush back thereon for receiving the bristles, means for inserting the bristles in folded form into said brush back, and mechanism operated by said hinged plate for swinging said bundler out to deliver the bundles of bristles to the said gripping device.

65 17. In a machine as specified, the combi-

nation with a bristle-receiving hopper and a feed follower therein, of a reciprocable separator for separating layers of bristles from those in the hopper, means for separating the bristles into bundles, a receiver, a rocking plate having gripping mechanism for conveying the bristles from the shuttle to the receiver, a toothed bundler hinged in a recess in said separator, and means for swinging said bundler out to deliver the bundles of bristles to the gripper, comprising a rod, the forward end of which is adapted to engage the bundler, a spring controlled rock arm connected at one end with one end of the rod, and a bar connected to the other end of the rock arm, the forward end of which extends forward in a position to be engaged by the rocking plate as it assumes a vertical position, and an adjustment screw in said plate which engages the end of said bar.

18. In a machine as specified, the combination with a bristle receiving hopper, and a feed follower therefor, of a toothed bar at the discharge end of the hopper for separating the bristles into separate bundles, a separator bar at the discharge end of the hopper and means for reciprocating the same across the end of the hopper to separate a row of bundles from those in the hopper, a toothed bundler pivotally mounted in a recess in the shuttle, and means for swinging said bundler out to deliver the bristles separated by said shuttle.

19. In a machine as specified, the combination with a bristle feeding hopper and a reciprocable separator at the discharge end of the hopper, for separating layers of bristles from those in the hopper, of means for defining the thickness of said layers, comprising adjustment screws threaded to projections on said hopper, and having annular grooves in their heads, and a vertically disposed plate having bifurcated ends which engage the grooved heads of the screws.

20. In a machine as specified, the combination with a bristle-holding hopper, a feed follower therein, means for dividing the bristles at the discharge end of the hopper into separate bunches, a means for separating layers of said bunches from the bristles in the hopper, and a receiving member for said bunches, of means for gripping said bunches and conveying them to a position above said receiver, comprising a rocking plate, a toothed stationary plate thereon, a toothed slidable plate movable in a slot in said stationary plate, the teeth on said plates having curved oppositely set coöperating edges, means for sliding the movable plate to grip the bundles separated by the separating means, a spring catch for locking said gripping plate in its gripping position, means for tripping said catch to release the movable gripping plate, when the rocking plate

stands over the receiver, and a spring for throwing the said plate to its normal position.

21. In a machine as specified, the combination with a bristle holding hopper, a feed follower therein, means for dividing the bristles at the discharge end of the hopper into bundles, means for separating layers of said bundles, from those in the hopper, 10 and a receiving member for said bundles, of means for gripping said bundles as they leave the shuttle and conveying them to a position above the said receiver, comprising a rocking member, a stationary plate there- 15 on substantially of the shape of an inverted U in cross section, the closed end being provided with teeth curved on one edge, a plate slidably mounted within the stationary plate, having teeth curved to coöperate with 20 those of the stationary plate, means including a cam for sliding said plate into gripping position, a spring catch on the locking member for locking said plate in such position, a cross-head and means carried there- 25 by for inserting the bundles carried by the gripper into the said receiver, a projection on the cross-head for engaging the trip to release the movable gripper, when the rocking member stands over the receiver, and a 30 spring for returning the movable plate to its normal position.

22. In a machine as specified, a base, an arm pivoted at one end to said base, a die on said arm adapted to receive a brush back, 35 said arm being adjustable to occupy any one of three positions, in combination with a frame, a bristle holding hopper mounted therein, means for receiving bristles from said hopper and for conveying them to a 40 position above said brush back, and means for inserting the bristles into apertures in the brush back.

23. In a machine as specified, a base, an arm, having an elongated hole in one end 45 and a pivot bolt which passes through said hole into said base, a spring for normally holding said arm at the limit of its inward

movement, a catch on the inner end of said arm and a wall on said base adjoining the inner end of the arm, having a notch, said 50 catch being held in the said notch by the said spring to position the arm parallel with the base, straps for holding the arm at inclined positions on either side of the first mentioned position, a block in the inner end 55 of the arm for receiving a brush back, said brush back and block having rows of registering apertures, the holes in each row of holes in the block being connected by grooves, in combination with a frame, a 60 bristle holding hopper therein, means for receiving bristles from the hopper and conveying them to a position above the said brush back, and means for inserting the bristles in the apertures in said brush back. 65

24. In a machine as specified, the combination with a base and an adjustable arm thereon, of a block having rows of apertures extending through the same and adapted to receive a bristle holding back correspondingly apertured, said block extending partially through a recess in said arm, a plate 70 slidable vertically in said recess, and pins carried by said plate which extend partially through the apertures in said block. 75

25. In a machine as specified, the combination with a support, of an arm pivoted thereto at its outer end, and having a slot extending vertically through its inner end, a block rigidly mounted in the upper por- 80 tion of said slot, having rows of holes extending through the same, and adapted to receive a bristle supporting back correspondingly apertured, headed pins at op- 85 posite ends of said slot, a plate slidable in said slot on said pins, and pins carried by said plate which extend partially through the holes in said block.

In testimony whereof I affix my signature in presence of two witnesses.

FRANK E. KRESS.
